United States Patent Office

Des. 218,199
Patented July 28, 1970

218,199

DOCUMENT REPRODUCING MACHINE

George D. Del Vecchio, Briscoe Cove, North Rose, and
Ruediger W. Knott, Rochester, N.Y., assignors to
Xerox Corporation, Rochester, N.Y., a corporation of
New York

Filed June 2, 1969, Ser. No. 17,434

Term of patent 14 years

Int. Cl. D16—05

U.S. Cl. D61—1

FIG. 1

FIG. 2

FIG. 3

FIG. 4

FIG. 5

FIG. 6

FIG. 1 is a front perspective view of a document reproducing machine showing our new design;

FIG. 2 is a front elevational view thereof;

FIG. 3 is an elevational view taken from the left side thereof;

FIG. 4 is an elevational view taken from the right side thereof;

FIG. 5 is a top plan view thereof; and

FIG. 6 is a rear elevational view thereof.

We claim:

The ornamental design for document reproducing machine, as shown.
